COMBINATION SASH BALANCE AND
WEATHER STRIP

Herbert K. Lundgren, Ripon, Wis.

Application December 12, 1940, Serial No. 369,823

6 Claims. (Cl. 20—52)

This invention relates to an improvement in a combined sash balance and weather strip and more particularly to an improvement in devices of this character which rely for their sash balancing function upon a coil spring.

The main objects of the invention are to provide a combined sash balance and weather strip structure wherein the coil spring and other parts are effectively housed or concealed so as to be thereby protected from the weather and whereby the structure when installed has a clean-cut, neat appearance free from suggestions of complicated mechanical construction; to provide such a structure which may be manufactured economically and at low cost and which may be easily installed either in new or old work; to provide a combined sash balance and weather strip which will be durable and efficient in use both in respect of its sash balancing function and its weather stripping function; and in general, it is the object of the invention to provide an improved sash balance and weather strip device of the character indicated.

Other objects and advantages of the invention will be understood by reference to the following specification and accompanying drawing wherein is illustrated a selected embodiment of the improved structure.

In the drawing:

Fig. 1 is a cross section through a window frame above the inner and outer sashes;

Fig. 2 is a side elevation of the window frame showing the parts of the improved sash balance and weather strip structure in place but with the sashes removed to more clearly illustrate the parts of the improved structure;

Fig. 3 is a perspective illustrating a step in the method of installing the improved structure;

Fig. 4 is a perspective of an end portion of a part of the improved structure;

Fig. 5 is a perspective of an end portion of another part of the improved structure; and

Fig. 6 is an end elevation of a part of the improved structure but showing a modified form of construction.

As shown in the drawing, inner and outer sashes 10 and 11, respectively, are vertically slidably mounted in a frame structure which comprises a member 12, an outer stop 13, an inner stop 14 and an intermediate stop 15. The stops 14 and 15 together with the intervening portion of the member 12 provide a way for slidably guiding the inner sash 10. The stops 13 and 15 and the intervening portion of the member 12 provide a way for slidably guiding the outer sash 11.

The inner and outer sashes 10 and 11 have their side edges grooved out as indicated at 16, the groove or way 16 extending from top to bottom of each sash.

5 The improved sash balance and weather strip comprises a main member 17 which comprises a base part 18 and a spring housing part 19. For convenience in production, the base part 18 and housing 19 are made separately and assembled 10 in the relationship shown. For this purpose, the housing part 19 is provided with a laterally outwardly extending flange 20 which is disposed in face to face relation with a marginal portion of the base member 18. Said flange 20 has a narrow marginal portion 21 re-bent so as to embrace a marginal portion of the base 18 to clamp the latter in assembled relation to the housing part. If desired, a series of indentations, such as indicated at 22, may be provided for more securely 15 locking the flange part 20 in predetermined relation to the base part 18.

As most clearly shown in Figure 1, the member 17 is positioned in the ways of the window frame with the base 18 disposed against the surface of the frame member 12. Anchoring of the member 17 to the window frame may be by any suitable means and adjacent either or both side edges of the member 17. Preferably, the member 17 is anchored to the frame member 12 by a series of vertically spaced nails or screws such as indicated at 23 which are disposed at one side of the base.

The housing part 19 is so formed that it will fit snugly in the groove 16 of the sash, it being understood that the weather strip structure is adapted to be made of light weight spring metal which may be flexed from an oversize so as to fit snugly within the groove 16. In other words, the housing 19 is initially made so that its cross-sectional expanse is somewhat larger than the corresponding cross-sectional area of the groove 16, so that when the housing part 19 is inserted in the groove 16, the housing part will be necessarily compressed somewhat. Hence, a desirable amount of friction is produced between the housing 19 and the walls of the groove 16 which serves to govern the slidability of the sash on the member 19. It will also be observed that the housing 19 may be 40 offset in its entirety either inwardly or outwardly of the plane of the sash so as to increase or decrease the tightness of the contact of either side of the housing with the adjacent side wall portion of the groove in the sash. Such offsetting 45 may be effected by bending the main member 17

in or adjacent the angle between the base flange 20 and the side wall portion of the housing 19 which extends from said flange.

It will be noted that due to the snug fit of the housing 19 in the groove 16 of the sash, a weather stripping effect results. Such weather stripping effect is preferably augmented by means of a flange formation 24 formed at the anchored edge of the base part 18 and arranged to frictionally engage the marginal portion of the sash. As clearly shown, the flange 24 is preferably bent inwardly, i. e., toward the sash, intermediate the edges of the flange, so that there is more or less of a cushioning effect produced which tends to maintain the sash in contact with the oppositely disposed stop. Thus there is a tight fit produced between the one face of the sash and a stop, and between the opposite face of the sash and the said marginal flange 24.

The base 17 is also preferably offset inwardly intermediate its width as shown in Figure 1 so as to also produce somewhat of a cushion or resilient arrangement for maintaining the sash 11 centered between the opposite sides of the window frame. The inward arching or buckling of the base part 18 also serves to avoid a tendency for the unsecured edge of the structure from separating from the window frame part 12 incident to the anchorage at the opposite edge of the base part.

A coil spring 25 of predetermined suitable strength is disposed within the housing 19 and it has one end hooked over the upper end of the base part 18 substantially as indicated at 26. Other means for anchoring the upper end of the spring 25 to the upper end portion of the member 17 may, of course, be employed but the described arrangement is practical and efficient.

The lower end of the spring 25 has its end hooked as indicated at 27 to the lower end portion of a window strip member 28 which is of the form shown in Figure 5.

The window strip 28 may be of metal somewhat heavier than the main member 17 and it comprises a base part 29 and a re-bent, hook-like part 30. The base part 29 is of such width that it may be secured by screws or otherwise as indicated at 31 to the side edge of the sash with its hook part 30 disposed within the area of the groove 16 in embracing relationship to a flange part 32 formed integrally with one wall of the housing part 19. As shown, the flange part 32 extends laterally inwardly from one side wall of the housing part 19 and it has its free edge re-bent or hemmed as indicated at 33.

The hook part 30 of the window strip 28 snugly embraces said hemmed edge 33 and constitutes, in effect, a further weather stripping in that the interfitting hemmed edge 33 and hook 30 serve to resist the passage of drafts therebetween.

The window strip 28 preferably corresponds in length to the vertical dimension of the sash as clearly shown in Figure 3 and the lower end of the spring 25 may be attached to the lower end of the window strip by punching a tongue-like member 34 out of the hook portion 30 to receive the hook formation on the lower end of the spring. It will be evident that lowering of the outer and normally upper sash 11 will be resisted by the spring 25. The frictional gripping effect between the various contacting parts already referred to is sufficient to hold the window in any desired lowered position against the

tendency of the spring to return the window to its normal upper position. However, slight manual force applied to the window is sufficient to move the window either upwardly or downwardly as may be desired.

The inner sash 10 is slidably mounted and resiliently supported by a spring structure enclosed with a housing 19 substantially in the same manner as already described in connection with the upper and outer sash. However, it is preferred (although not necessary) to reverse the positioning of the sash balance and weather stripping parts as clearly indicated in Figure 1.

As there shown, the main member 17 is anchored to the frame adjacent the outer edge of the member 17 and the laterally extending flange part 24 of the main member cooperates with the outer face of the sash rather than with the inner face as in the case of the upper sash.

Also, in the reversed arrangement, the window strip 28 is secured to the edge portion of the sash outside of the groove 16 therein instead of to the portion inside of the groove as in the case of the upper sash.

In the case of the lower sash, the counterbalancing spring is maintained in a stretched or extended condition so that it will assist in the upward movement of the lower sash which is more often opened than the upper sash. The spring

30 for the inner or lower sash has its upper end anchored to the upper end of the main member 17 by being hooked thereover as shown and the lower end of the spring is secured to the lower end of the sash strip 28 adjacent the lower edge of the sash substantially in the same manner as explained in respect of the upper sash. However, if desired the spring for the inner sash may have its lower end secured to the window strip 28 adjacent the upper end of the strip and adjacent the upper end of the said sash. In that case, a different spring would be required whereas when the arrangement is as shown in Figure 2, the same type of spring may be employed for both the inner and outer sashes.

45 To install the described structure, a sash strip such as 28 is secured to the sash and a main member 17 is assembled with the sash and caused to interlock with the hooked part of the sash strip. The spring 25 may first have its lower end secured to the lower end of the sash strip

50 and after assembly of the main member 17 with the sash and sash strip, the upper end of the spring may be hooked over the upper end of the said main member 17. The spring will then tend to maintain the sash in elevated position with its upper end substantially flush with the upper end of the main member 17. The sash with the weather strip and balance structure thus associated with its opposite sides may then be inserted in the window frame, the stops 14-15 being first removed to permit insertion of the outer sash, and only the stop 14 being removed to permit similar insertion of the inner sash.

55 The fastening means 23 may then be applied to the then downwardly extending portions of the main member 17, after which the sashes may be moved downwardly and the fastening means applied to the then upwardly extending portions.

In the modified construction shown in Figure 6, the main member is designated 17a. It corresponds substantially to the member 17 of the preferred form of construction and differs therefrom in that the base part 18a is in flat form, and in that the base part 18a and the housing part 19a are integrally formed with the result-

ing elimination of the seam formed by the re-bent part 21 in the first described construction. The modified construction shown in Figure 6 is somewhat more difficult to produce in that it requires larger and more expensive forming equipment but there is no substantial benefit gained by this more expensive form of construction.

The described construction completely encloses the counterbalancing springs which are thereby effectively protected from the weather and whereby the spring is concealed from view with corresponding improvement in the general appearance of the structure. Various kinds of metals or alloys or combinations of metals may be employed and various changes in the described structure may be made without departing from the spirit of the invention, the scope of which should be determined by reference to the following claims, the same being construed as broadly as possible, consistent with the state of the art.

I claim:

1. A sash balance comprising a base member and a tubular housing, the housing having opposed side portions connected together at their outer edges, one of said side portions having its other edge connected to said base member and the other of said side portions having its other edge provided with a flange extending inwardly of the housing in spaced relation to said base member, a sash strip having a portion extending into said housing between said flange and said base member and re-bent around said flange and another portion extending outwardly from said housing for attachment to a sash, and a spring disposed within said housing and having its opposite ends connected respectively to said base member and said strip.

2. A sash balance comprising a base member and a tubular housing, the housing having opposed side portions connected together at their outer edges, one of said side portions having its other edge connected to said base member and the other of said side portions having its other edge provided with a flange extending inwardly of the housing in spaced and approximately parallel relation to said base member, a sash strip having a portion extending into said housing between said flange and said base member and re-bent around said flange and another portion extending outwardly from said housing for attachment to a sash, and a spring disposed within said housing and having its opposite ends connected respectively to said base member and said strip.

3. A sash balance comprising a base member and a tubular housing, the housing having opposed, relatively spaced side portions interconnected at their outer edges and one of which side portions extends laterally from said base member in inwardly spaced relation to one edge of the latter and is connected to said base member, the other of said side portions being disposed in laterally extending relation to said base member in inwardly spaced relation to the other edge thereof, said other side portion having a free edge provided with a flange extending inwardly of the housing in spaced relation to said base member, a sash strip having a portion extending into said housing between said flange and said base member and re-bent around said flange and another portion extending outwardly from said housing for attachment to a sash, and a spring disposed within said housing and having its op-

posite ends connected respectively to said base member and said strip.

4. A sash balance comprising a base member and a tubular housing, the housing having opposed side portions one of which is connected to said base member and the other of which is provided with a flange extending inwardly of the housing in spaced relation to said base member, there being also a front portion integrally connecting said housing side portions, said housing being formed of spring material and of such shape that said side portions are relatively compressible, a sash strip having a portion extending into said housing between said flange and said base member and re-bent around said flange, a portion of said strip extending outwardly of said housing for attachment to a sash, and a spring disposed within said housing and having its opposite ends connected respectively to said base member and said strip.

5. In a spring balance for a sash which is vertically slidably mounted in a guide-way in a window frame, the combination of a vertically elongated, outwardly facing U-shaped housing adapted to be recessed into the side edge of the sash so that the sash is slidable thereover, a pair of flanges extending laterally in the same direction from the free edges of the respective side portions of said U-shaped member, one of said flanges constituting a base flange adapted to be secured to the bottom wall of the guide-way in which the sash is slidable, thereby to hold said housing in fixed position, the other of said flanges being disposed in inwardly spaced relation to the plane of said base flange so as to provide an access opening intermediate said bottom wall of the guide-way and said other flange, a coil spring disposed within said housing, and a spring-to-sash connector comprising an inner part disposed intermediate said housing side portions and connected to said spring within the housing, and an outer part extending from said inner part and extending through said access opening into overlying relation to an edge portion of the sash for securement thereto.

6. In a spring balance for a sash which is vertically slidably mounted in a guide-way in a window frame, the combination of a vertically elongated, outwardly facing U-shaped housing adapted to be recessed into the side edge of the sash so that the sash is slidable thereover, a pair of flanges extending laterally in the same direction from the free edges of the respective side portions of said U-shaped member, one of said flanges constituting a base flange adapted to be secured to the bottom wall of the guide-way in which the sash is slidable, thereby to hold said housing in fixed position, the other of said flanges being disposed in inwardly spaced relation to the plane of said base flange so as to provide an access opening intermediate said bottom wall of the guide-way and said other flange, a coil spring disposed within said housing, a spring-to-sash connector comprising an inner part extending into said housing intermediate said housing side portions and connected to said spring within the housing and an outer part extending from said inner part and extending through said access opening into overlying relation to an edge portion of the sash for securement thereto, and resilient means bearing against one side of the sash to yieldably resist sliding movement thereof.
